SIDE FRAME

Filed Feb. 27, 1929

UNITED STATES PATENT OFFICE

DONALD S. BARROWS, OF ROCHESTER, NEW YORK, ASSIGNOR TO THE SYMINGTON COMPANY, OF NEW YORK, N. Y., A CORPORATION OF MARYLAND

SIDE FRAME

Application filed February 27, 1929. Serial No. 343,066.

This invention relates to side frames for railway car trucks and, more particularly, to improving the strength of connection between said frames and integral journal boxes 5 at the ends thereof.

The principal object of my invention, generally considered, is to improve the general appearance of cast metal side frames integrally formed with journal boxes at their 10 ends and consolidate in the main core the strengthening ribs or brackets generally provided adjacent the junctions between the frame and boxes, thereby doing away with reinforcing flanges at said junctions.

Another object of my invention is to improve the connection between integral journal boxes and their associated frames by 15 widening and downwardly convoluting the web of the tension member for its entire width to provide a hollow bracket between said member and the adjacent side wall of the box, the lower edge of said bracket preferably extending straight to the side wall of the box, the side walls of said bracket being flared upwardly away from each other to form a construction V shape in cross section, the flanges of the member at the widened portion of the 20 web being correspondingly outwardly flared or convoluted to join with the edges of said 25 web.

A further object of my invention is to provide a side frame with integral journal boxes, the roofs of said boxes being preferably beveled rearwardly of the front flange of the 30 tension member with the web of the member sloping generally in line with the beveling of the journal box roof, the connection between the tension member or junction between said tension and compression members 35 and journal box being reinforced by increasing the width of the tension member web and downwardly convoluting it for the full width thereof, the flanges of said member being outwardly convoluted or corrugated adjacent the junction with the box to meet the side edges of the widened portion of said web.

A still further object of my invention is to provide a side frame and integral journal box 40 construction in which the connection with the box is rigidified and all strengthening ribs

or brackets consolidated in the main core, thereby eliminating flared flanges at the junction of the tension member and box, this being accomplished by increasing the width of the tension member web and forming a depending V shaped corrugation in said web for preferably the full width thereof, the side flanges of said tension member being diverted or flared outwardly to the outer edges of said convoluted portion of the web.

Other objects and advantages of the invention relating to the particular arrangement and construction of the various parts will become apparent as the description proceeds.

Referring to the drawing illustrating my invention, the scope whereof is defined by the appended claims.

Figure 1 is a fragmentary sectional view of one end of a side frame and integral journal box embodying my invention, said section being taken on the line 1-1 of Figure 3 looking in the direction of the arrows.

Figure 2 is a transverse sectional view on the line 2-2 of Figure 1 looking in the direction of the arrows.

Figure 3 is a fragmentary horizontal sectional view on the line 3-3 of Figure 1 looking in the direction of the arrows.

Figure 4 is a fragmentary longitudinal sectional view on the line 4-4 of Figure 3 looking in the direction of the arrows.

Figure 5 is a fragmentary perspective view of a portion of the front of the box and the tension member adjacent the junction between said box and member.

Figure 6 is a fragmentary perspective view of the back of the box and a portion of the tension member adjacent the junction between said box and tension member.

Referring to the drawing in detail, like parts being designated by like reference characters, there is shown a side frame 1 of the cast type comprising a tension member 2 and a compression member 3 united at their ends and to integral journal boxes 4, only one of which is illustrated. Although only a fragmentary portion of the frame is shown, it will be understood that the construction is an improvement of the type of frame illustrated and described in the Hankins Patent

No. 1,637,696 of August 2, 1927, and said frame has a compression member and a tension member spaced at intermediate portions by struts or bolster guide columns, the tension and compression members converging 5 at their ends and united together and to integral journal boxes. As those portions of the frame, not illustrated, are of well known construction, it is not deemed necessary to show any more than the novel features which will 10 now be pointed out.

In the Hankins patent above referred to, the connection between the tension member and each box was reinforced by a pair of web portions spaced from the junction between 15 the web of the tension member and box and from each other, thereby necessitating a separate core. In the present case, the connection between the tension member 2, which is preferably channel shape in cross section and comprises a lower web 5 and upstanding flanges 6, and the journal box 4 is reinforced by a bracket 7 approximately V shape in cross section, as illustrated particularly in Figure 2. 20 Said bracket is preferably formed by increasing the width of the tension member web adjacent the junction with the journal box and downwardly corrugating said web for the entire width thereof, the corrugation 25 extending away from the adjacent wall of the box and gradually decreasing in depth and width to finally merge into the normal web of the tension member, as illustrated particularly in Figures 1, 3 and 4.

30 The journal box is preferably beveled at its upper corners rearwardly of the front flange 6 of the tension member or that portion of the frame after the union between the tension and compression members, said beveling being preferably produced by sloping 35 the roof of said box downwardly and outwardly from the planes of the inner walls of the brass lugs 8 and 9, said sloping preferably corresponding with the general inclination 40 of the web 5 of the tension member 2, so that the tension member web forms, in effect, a continuation of the sloping portion of the roof at the adjacent side wall of the box.

45 For further reinforcing the connection between the frame 1 or the tension member 2 thereof, and the journal box 4, the flanges of the tension member are sloped outwardly or correspondingly convoluted to meet the side edges of the widened portion of the web 50 so that outwardly extending hollow embossments or corrugations are also provided in the flanges of the tension member, said corrugations being greatest adjacent the junction between the tension member and the roof of the 55 box and decreasing or tapering both ways to finally merge into the normal planes of the flanges of said tension member, as most clearly indicated at 10 and 11. This construction obviates the necessity of external gusset 60 flanges and substitutes outstanding hollow

brackets or convolutions which are produced by the main core, thereby avoiding the necessity of separate cores and facilitating the manufacture of the frame.

The sloping or tapering portion 10 of the tension member or frame flange 6 over the forward or outer portion of the box may correspond generally with the corresponding portion 11 over the inner or rearward portion

70 of the box, except that the forward portion of the box does not have the edges beveled like the rearward portion, as shown most clearly in Figure 3. The beveling 12 adjacent the junction between the box and tension member

75 may extend between the flanges 6 of the tension member as well as rearwardly thereof. The construction adjacent the outer side wall of the box may correspond, but in the present embodiment is shown as of somewhat different formation, in that in addition to being

80 beveled downwardly and outwardly, the corners produced where the walls 13 and 14 of the outer brass lug 9 and the outer side wall 15 of the box meet the beveled portion are

85 cut off by planes angularly disposed with one another to provide the portions 16 and 17 sloping, not only downwardly and outwardly, but toward each other as well. This construction improves the general appearance of

90 the frame and results in a slight economy in material and improvement in the strength of the box adjacent the outer brass lug. The inner brass lug 8 may be formed to correspond generally with the outer brass lug 9,

95 but in the present embodiment is shown as provided with parallel side walls 18 and 19 and an inner side wall 20, the upper end of

100 said inner side wall being deflected outward, as indicated at 21, to meet the beveled portion 12 of the box at approximately right angles.

105 From the foregoing description taken in connection with the accompanying drawing, it will be seen that I have improved the construction, strength and general appearance of cast side frames with integral journal boxes

110 by reinforcing the connection between the tension member and box by means of a bracket formed as an integral depending convolution or corrugation generally V shape in section,

115 in the web of the tension member where said web is widened at the junction with the box, the lower edge of said convolution preferably meeting the adjacent wall of the box at the bottom of the corresponding brass lug. The convolution or hollow connecting bracket is

120 preferably wider than the normal width of the tension member at the junction with the box, but tapers or decreases in width away from said box to gradually merge into the normal web portion of the tension member.

125 The flanges of the tension member or the side walls of the frame at the junction between the tension and compression members are diverted outwardly to meet the side edges of

130 the widened portion of the web and inwardly

of the corresponding side wall of the box to meet the roof of the box, thereby resulting in a further improvement in strength of connection between the side frame and box. The 5 aforescribed construction results in consolidating in one main core all strengthening ribs and brackets, thereby facilitating the manufacture of the frame.

Although a preferred embodiment of my 10 invention is illustrated and described, it will be understood that modifications may be made therein within the spirit and scope of the appended claims.

Having now described my invention, I 15 claim:

1. A truck side frame comprising a tension member, a compression member, said members united together at their ends, a journal box integrally united to each end of the frame, 20 said tension member being channel shape in cross section with the web of the channel sloping generally in the direction of the upper inner corner of the adjacent brass lug, the connection between said tension member 25 and box being rigidified by widening the web of said member and downwardly convoluting it for the full width and extending it to join with the adjacent side wall of the box, the flanges of said tension member being flared 30 downwardly and outwardly to the outer edges of said widened web portion.

2. A truck side frame comprising a tension member, a journal box with brass lugs integrally united to an end of said member, said 35 tension member being channel shape in cross section with the web of the channel sloping generally in the direction of the upper inner corner of the adjacent brass lug, the connection between said tension member and box 40 being strengthened by widening and downwardly convoluting the entire web of said tension member and extending it to join the side wall of the box, the flanges of said member being diverted downwardly adjacent their 45 lower edges to join with the outer edges of said web.

3. A truck side frame comprising a tension member, a journal box with brass lugs integrally united to one end of said member, said 50 member being channel shape in cross section, the roof of said journal box being beveled rearwardly of the front flange of said tension member from the transverse planes of the inner sides of the brass lugs, the web of the tension member sloping generally in line with the corresponding beveled portion, the connection between said tension member and box being reinforced by flaring the web of said member in width at the junction with 55 said box and downwardly convoluting it to generally V shape in cross section for its entire width, the flanges of said tension member flaring downwardly and outwardly to the outer edges of said V shaped cross section.

65 4. A truck side frame comprising a ten-

sion member, a journal box integrally united to an end of said member, the connection between said tension member and box being rigidified by widening and downwardly convoluting the web of said member for the entire width thereof, the flanges of said member being bent outwardly to joint with the outer edges of said widened portion and provide hollow convolutions extending outwardly from the sides of the tension member, and tapering both ways from the junction between said member and box to gradually merge into the sides of said member.

5. A truck side frame comprising integrally formed tension and compression members and journal boxes at the ends of said members, the junctions between said boxes and frame being reinforced by providing hollow convolutions bulging outwardly from the sides of the tension member at the 85 junctions with the boxes and tapering both ways from said junctions to gradually merge into the sides of the tension member, the web of said member being correspondingly widened and downwardly convoluted for 90 its full width to meet the corresponding side walls of said boxes.

6. A truck side frame comprising a tension member formed U shape in cross section with a lower web and upstanding flanges, a 95 journal box integrally connected to one end of said frame, the junction between said frame and box being rigidified by a depending hollow convolution for the full width of the web of said tension member, and laterally 100 extending hollow convolutions in the side walls of the member, said web being correspondingly widened and extended to the adjacent side wall of the box, the laterally extending convolutions joining the roof of the 105 box on the one hand and the outer edges of the convoluted portion of the web on the other.

7. A truck side frame comprising a compression member, a tension member, a journal box integrally united to said members adjacent the junction therebetween, said members being generally channel shape in cross section with flanges merging adjacent the junction with the box, said junction being reinforced by increasing the width of the tension member web and downwardly corrugating it to approximately V shape in cross section for the full width thereof, said web being extended to join the adjacent side wall of the 115 box, the flanges of said member being caused to diverge laterally to meet the side edges of the widened portion of the tension member web and provide hollow corrugations extending from the sides of said flanges.

8. A truck side frame comprising integrally formed tension and compression members and journal boxes at the ends of said members, the junction between said boxes and frame being reinforced by increasing 130

the width of the tension member and downwardly corrugating the lower wall thereof for the full width adjacent the junctions with the journal boxes, the remaining walls of said tension member being outwardly flared to join the side edges of the downwardly corrugated wall of said member.

In testimony whereof I affix my signature.

DONALD S. BARROWS.
